UNITED STATES PATENT OFFICE.

EDWIN E. FREDERICK, OF BRIDGEVILLE BOROUGH, PENNSYLVANIA.

GLOBE-HOLDER.

1,064,895.

Specification of Letters Patent. Patented June 17, 1913.

Application filed December 31, 1912. Serial No. 739,473.

To all whom it may concern:

Be it known that I, EDWIN E. FREDERICK, a citizen of the United States, and residing in the borough of Bridgeville, in the county 5 of Allegheny and State of Pennsylvania, have invented or discovered new and useful Improvements in Globe-Holders, of which the following is a specification.

My invention consists of a new and improved 10 spring holder for globes, shades and similar articles, and it is especially intended for use in connection with depending lighting fixtures, such as inverted incandescent gas lights.

The objects in view are to facilitate the 15 installation or removal of the globe, to properly center the same in relation to the fixture, and to prevent its accidental dislodgment.

In the accompanying drawings, Figure 1 20 is an elevation showing my invention applied to an inverted incandescent gas fixture; Fig. 2 is a section of the same along the line II—II in Fig. 1 looking in the direction of 25 the arrow and showing the spring clamp in its normal or contracted position assumed in holding the globe; Fig. 3 is a similar view showing the said spring clamp expanded to permit the insertion or removal of the globe; Fig. 4 is a perspective showing the spring 30 clamp removed from the canopy; Fig. 5 is a view similar to Fig. 2 showing a slight modification, and Fig. 6 is a view similar to Fig. 3 showing the same modification.

The following is a detailed description of 35 the drawings.

A is an inverted incandescent gas light fixture wherein 1 is the gas check, 2 the mantle support, and 3 the depending canopy 40 from which the globe is to be suspended. Said canopy is usually stamped of sheet brass or other suitable material and is provided with a depending annular flange 4.

5 are the ports in said canopy for the 45 escape of the products of combustion. The spring clamp member B is mounted in said flange 4.

The member B is formed by bending up 50 into annular form a length of resilient wire or similar material having its end portions 6 and 7 overlapping. The extreme ends 8 and 9, respectively, are bent outwardly at an angle. The end portion 6 lies in the arc of the circle described by the body of the member B, while the end portion 7 lies in an arc 55 of larger radius, as shown in Fig. 4. Inter-

mediate of its ends the annulus B is provided with an integral radial loop 10 whose end is preferably upturned as at 11.

In mounting the clamp member B in the 60 flange 4, the loop 10 is inserted through a slot 12 in flange 4, the upturned portion 11 of said loop preventing its accidental withdrawal. The end 8 is inserted through a slot 13 and the end 9 is inserted through a 65 hole 14.

15 and 16 are knobs fixed on the ends 8 and 9, respectively, forming a convenient means for operating the clamp and preventing the accidental withdrawal of the ends 70 from the flange 4.

When the clamp B is in its contracted or gripping position shown in Fig. 2, the loop 10 tends to bear against one end of the slot 12 and the end 8 tends to bear against the 75 corresponding end of slot 13, thus controlling the contraction of the member B. When said member is expanded to the form shown in Fig. 3, the loop 10 and end 8 bear against the other ends of their slots, thus 80 limiting the expansion of the member B. The end 9 is held in position at all times in its hole 14.

The member B may be expanded by pressing the knob 15 toward the knob 16, the 85 latter being used for leverage. By this means the end 8 and loop 10 are caused to slide in their respective slots, permitting the member B to expand and at the same time maintain its annular form. Thus the 90 neck of the globe may be inserted into or withdrawn from the clamp without tilting. When the knob 15 is released, the member B contracts to its normal diameter, as shown in Figs. 2 and 4, still maintaining its annular 95 form and resiliently yet snugly gripping the neck of the globe throughout substantially its entire circumference. Thus the globe is held snugly against rattling. Without the provision of lateral movement of loop 10 such functions could not be performed. The clamp would not at all times maintain the form of an annulus and the globe would be tilted to insert or remove it, 100 and the grip of the resilient clamp would be interrupted. By maintaining the member B in the form of a true annulus, having its center substantially coinciding with the center of the canopy 3, the globe is properly centered and presents an attractive appearance.

In the modification shown in Figs. 5 and

6, the annulus is provided with two loops 10, instead of but one loop, seated in a like number of prolonged slots 12. The operation and function of the spring clamp B 5 is the same as above described.

The holder is neat, inexpensive yet containing no parts likely to be broken or wear out, and is convenient and efficient in the installation, removal and support of the globe.

10 What I desire to claim is:—

In a globe-holder, an annular flange provided with slots, a resilient wire bent into an annulus with overlapping and outward-bent ends, one of said ends being projected 15 through said flange, a knob secured to said projecting end and holding the same against movement, the other of said ends extending through and being slidable in one of said

slots, said last-mentioned end being movable in its slot toward said first end to expand the annulus, and a radial loop formed in the intermediate portion of said annulus and extending through the other of said slots, said loop moving laterally in its slot toward the movable end of said annulus 25 when the latter is expanded and moving in its slot toward the fixed end when said annulus contracts to its normal diameter, whereby said annulus expands and contracts uniformly. 30

Signed at Pittsburgh, Penna., this 30th day of December 1912.

EDWIN E. FREDERICK.
